SORTING MACHINE

Michael Maul, Berlin-Johannisthal, Germany,
assignor to the firm Deutsche Hollerith Ma-
schinen Gesellschaft M. b. h., Berlin-Lichter-
felde, Germany

Application May 11, 1939, Serial No. 273,015
In Germany May 25, 1938

2 Claims. (Cl. 209—110)

The present invention relates to machines for sorting perforated records in which the character representation is provided in a plurality of adjacent card columns. Such records are adapted to represent a plurality of different characters and it is the purpose of a sorting machine to sort such records so as to selectively segregate the records in accordance with the character representation.

One form of record which has, heretofore, been capable of being sorted by machines of a well known type comprises cards which represent the characters in vertical columns. In sorting machines of the well known type the cards to be sorted are passed through the machine in the direction of the columns, that is, the direction of card feed is in the same direction as the card columns. For selecting the columns which are to control sorting operations it has been the usual practice to mount the analyzing device in such a manner that it may be adjusted manually so as to coordinate the analyzing device with the selected card column.

It is further well known that such sorting operations are effected on a large number of records and it is desirable that the output of such machines be high so as to effect the economical utilization of such machines. For obtaining such high output it is desirable and necessary that the card cycle be as short as possible so that for a given period of time a maximum number of cards may be fed. The cards which are to be sorted by such machines are usually rectangular in shape and the short machine cycle is derived by moving the card through the machine in the direction of its shorter dimension which is parallel to the columnar arrangement or, in other words, transversely with respect to the longer dimension of the card. By feeding cards in this way the card cycle is made as short as possible and permits a relatively high output in sorting operations.

In contradistinction to the type of card heretofore described, the present machine is devised to effect the sorting of cards of a different type. Such records consist of a plurality of superimposed card fields, one arranged above the other, wherein each card field consists of a plurality of card columns for the character representation. Such type of card has been devised for the purpose of a better utilization of card capacity and if cards of this type were sorted by machines of the construction previously described they would necessarily have to be fed in a direction corresponding to the longer dimension of the record, which would require an extension in the time of machine cycle of operation, or conversely, decrease the output of the sorting machine.

The main object of the present invention is to provide an improved form of sorting mechanism which permits the cards of the last described type to be passed through the machine in the direction of the shorter length of the card, such sorting operations being effected by the successive analysis of the card columns, which are arranged transverse to the direction of card feed. The above construction enables high speed in sorting operations without, however, requiring the card to be passed through the machine in a columnar direction, as would be required by machines heretofore constructed and thus decrease the output in sorting operations.

5 A still further object of the present invention is to provide a manually adjustable means for selecting the card field which is to control sorting operations.

Another object of the present invention is to 10 provide an improved means for effecting the selection of the column in the selected card field which is to control sorting operations. Preferably this consists of a manually adjusted column selector contact and also a contact member rotating synchronously with the card feed, and which at each rotation makes contact with the column selector at predetermined times in the machine cycle so as to render the analyzing device effective at the time the selected card column is coordinated therewith.

15 A still further object of the present invention is to provide a storing mechanism which consists of two sets of set-up devices. According to the principle of operation of this storing mechanism the set-up of the character representation is to be stored up in the first set during one cycle and transferred to a second storing set to 20 control sorting of the card in a successive cycle.

25 The first storing set will then be cleared so as to receive a set-up under control of the next card. During the subsequent cycle the assorting of the card analyzed in the preceding cycle will take place and the control of the sorting blades will then be effected by the second set, which as 30 follows from the previous explanation, is adjusted in accordance with the card analyzed with preceding cycle. Of course, at a certain time the set-up of the second set is cleared out. The set-up of the first set will then be transferred to 35 the second set and thereafter, the first storing set will be cleared out.

40 Obviously, the first storing set receives the set-up under control of the cards, while the second set-up controls the adjustment of the sorting blades in accordance with the card analyzed during the preceding card cycle.

45 The above arrangement is similar in principle of operation to that disclosed in the patent to Maul, No. 2,025,602, dated December 24, 1935, 50 but differs herein in certain structural details.

Further objects of the instant invention reside in any novel feature of construction or operation or novel combination of parts present in the embodiment of the invention described and shown in the accompanying drawings whether within or without the scope of the appended claims and irrespective of other specific statements as to the scope of the invention contained herein.

In the accompanying drawings:

Fig. 1 is a longitudinal sectional view of the right end of the machine.

Fig. 2 is a transverse sectional view taken on the line 2—2 of Fig. 1.

Fig. 3 is a sectional view taken on an enlarged scale and is taken on the line 3—3 of Fig. 1.

Fig. 5 is a view in side elevation of the machine.

Fig. 6 is a view in side elevation of the assembled sorting machine and is shown on a much reduced scale.

Fig. 7 is a plan view of the preferred form of card capable of being sorted by the present machine.

Fig. 8 is a code showing the different combinations of perforations for representing a series of numbers.

Fig. 9 is an electrical wiring diagram of the machine.

Card feeding mechanism

Card feeding operations are effected in a manner which is usual in the type of machine herein disclosed. The driving motor 11 drives through a belt a longitudinal driving shaft 18 (Fig. 5) which drives by means of worm gears 19 a plurality of sets of transversely arranged feeding rollers 13, best shown in Fig. 1. By means of a worm gear 22 (Fig. 2) a shaft 36 is rotated by the driving shaft 18. The shaft 36 (Fig. 1) has a crank arm connection to a slidably mounted frame which carries the usual picker knife 12, as shown in Fig. 1. The cards are placed in the magazine which is formed by means of uprights 10 so that for each reciprocation of the picker knife 12 a single card will be fed from the bottom of the stack to the first set of feeding rollers 13, thereafter to a set of analyzing brushes 16 and from said analyzing brushes, by means of the remaining sets of card feeding rollers 13, to sorting blades and thence to a selected card pocket. When the leading edge of the perforated card leaves the second set of rollers, it is fed beneath the staggered ends 33 of the electromagnetically actuated sorting blades so that by the positioning of the sorting blades, in a manner to be subsequently explained, the card will be fed by the other sets of rollers 13 to a selected card pocket. Each of the card pockets, as best shown in Fig. 1, is provided with a spring-urged bottom plate 24 upon which the sorted cards fall and in accordance with the weight of the cards deposited thereon, the bottom 24 will accordingly be positioned.

Form of cards to be sorted

Figure 7 is an illustration of the preferred form of record capable of being sorted by the present machine and comprises three superimposed card fields, each of said card fields comprising fifteen columns for the representation of a corresponding number of characters. The code for representing the digits is shown in Fig. 75

3 and attention is directed to the fact that provision is also made for representing the numbers 10, 11 and 12 since for some types of character designation, these numbers are utilized for representing month, days of months, etc. The machine is provided with thirteen sorting pockets, only two of which are shown in Fig. 11, but all are shown in Fig. 6. As is usual in the type of machine herein disclosed an extra sorting pocket, which is termed a "reject" pocket R, Fig. 6, is also provided for receiving imperforate cards, and also cards of those groups which are not to be sorted out.

Card analyzing means

The cards are fed through the machine in the direction of the arrow shown in Fig. 9 so that for a selected card field the card columns will be analyzed column by column, in the direction of the arrow, which corresponds to the shorter dimension of the card. To effect the successive analysis of the card columns the card analyzing brushes are arranged transversely of the direction of card feed so as to intercept such holes. The analysis of the card columns is preferably effected electrically by means of a series of four analyzing brushes 16 which are carried by a brush holder 15 and the analyzing brushes comprise flexible wires which press upon the card so as to pass through the holes at the index point positions and make electrical contact with a contact plate 17. The analyzing brushes 16 thereby concurrently analyze the holes arranged in each card column.

Selection of card fields

As previously described, the cards to be sorted comprise three superimposed card fields, and for effecting the selection of the card fields the analyzing brushes 16 are adapted to be positioned so as to be coordinated with the desired card field, resulting in the analysis of the successive card columns thereof. The brush holder 15 is loosely mounted or pivoted upon a rod 14 and is provided with a handle 41 (Figs. 1 and 2) which is operable exterior of the machine so that by moving the handle 41 laterally the analyzing brushes may be coordinated with a selected card field. The rod 14 is provided with three grooves 42 (Fig. 2) and cooperating with such grooves so as to impositively retain the brush holder 15 in a desired position is a spring-pressed aligning ball 43 (see Fig. 1). As shown in Fig. 2, the intermediate card field will be analyzed by the position of the brush holder 15 shown in this figure but by manually positioning the brush holder 15 to either the left or right, as viewed in Fig. 2, the analyzing brushes 16 will be coordinated with the respective card field.

For the purpose of providing continuous electrical contact with the brushes 16 irrespective of the position of the brush holder 15, the latter carries contact springs 44 (Fig. 1) which have electrical contact with the respective brushes 16 and also bear against current supply bars 45 carried by a stationary bar of insulating material. By the above construction, current may be transmitted to the brushes from the bars 45 in the different positions of the brush holder 15.

Selection of controlling card column of selected card field

The construction of the selecting mechanism provided for selecting a certain card column of a selected card field is best disclosed in Figs.

2 and 9. Upon a shaft 50 which is journaled in a pair of side frame plates 46 and which extends to the right from the right-hand frame plate 46, as best shown in Fig. 2, there is loosely mounted thereon a sleeve 48. To the sleeve 48 there is secured a gear 49 which is driven by a gear secured to the driving shaft 36 by an intermediate idle pinion. The gear ratio is so selected that for each revolution of the shaft 36, which is effected for each card sorting cycle, the gear 49 and the sleeve 48 will be rotated a single revolution. To the sleeve 48 there is secured a disc 51 formed of some suitable insulating material and carrying a contact point 52. The contact point 52 is in electrical contact with a current supply ring which is carried by the insulating disc 51 and against this current supply ring there is urged a spring-pressed contact ball 57, as best shown in Fig. 2, but shown diagrammatically in Fig. 9 as a resiliently urged contact plate 57. By means of the above construction electrical current is continuously conducted to the contact point 52 during the rotation of the disc 51.

Secured to the shaft 50 is a disc 54 of insulating material and which carries a spring-pressed contact member 53, the left end of which (see Fig. 2) makes continuous electrical contact with a current supply ring 55, and the right end of which is adapted at a certain time to make electrical contact with the aforementioned contact point 52.

To the shaft 50 there is secured an indicator 31 bearing the numbers 1 to 15, inclusive, and which are individually visible through an aperture 30 provided in a cover plate for the indicator 31. To the shaft 50 there is also secured a knob 32 by means of which the shaft 50 may be rotated to a position which corresponds to the selected card column which is to control sorting operations. The disc 54 is provided with fifteen aligning notches against which bears a spring urged aligning member 56 which impositively holds the disc 54 in a desired position. Since, for each card field there are fifteen columns, the disc 54 may be adjusted so as to bring the contact member 53 to any one of fifteen different positions, so that during each revolution of the disc 51 the rotatable contact element 52 will make contact with the adjustable contact member 53 at a point in the cycle when the selected card column is coordinated with the analyzing brushes 16.

Therefore, with a desired adjustment of the knob 32, corresponding to the selected card column, an electrical contact will be made by the column selecting mechanism, which has just been described, at a point in the cycle corresponding to the coordination of the selected card column with the analyzing brushes, thereby closing at such time in the card cycle a circuit from a wire 101 through the column selecting mechanism to a wire 102, as diagrammatically shown in Fig. 9.

Sorting mechanism

In order to selectively guide the cards to be sorted into the different pockets a sorting arrangement comprising a series of adjustable sorting blades of a well known type is preferably provided for the present machine. The mechanism for sorting the cards is fully shown and described in the patent to Michael Maul, No. 2,025,602, dated December 24, 1935, to which reference may be had for further details of construction and operation. However, in order to more clearly understand the present invention a general descrip-

tion of the sorting mechanism will be given herein.

Resting upon the armature of a sorting magnet 21 (Fig. 1) are the staggered ends 33 of a plurality of sorting blades, there being provided one sorting blade for each of the sorting pockets, and the left end of each blade terminates at the respective sorting pocket so as to cause the card to be sorted to be guided into the related sorting pocket. In the event that the sorting magnet 21 is not energized, and its armature will remain unattracted, the card will be fed by the rollers 13 beneath the staggered ends 33 of all of the sorting blades and, guided by the armature of the magnet 21 and a sorting blade, the feeding rollers 13 will thereupon feed such card to the first pocket R shown in Fig. 6, and which pocket is usually known as the "reject" pocket.

However, in the event that the sorting magnet 21 is energized, at the time of its energization the leading edge of the card will be fed by the rollers 13 so as to be beneath a certain number of the ends 33, and the attraction of the armature of the magnet 21 will permit the ends of the remaining sorting blades to move downwardly since they are not held upwardly by the card to be sorted. As the card is fed further the card will be fed above such sorting blades, and will be guided by one of the sorting blades so as to be disposed in the related sorting pocket. In general, the position of the leading edge of the card with relation to the ends of the sorting blades at the instant of the energization of the sorting magnet 21 will determine into which sorting pocket the card will be guided. For carrying out this operation the sorting magnet 21 must be energized by receiving electrical impulses effected at differential times in accordance with the characters or digits which are to control sorting operations. This is obtained by means of an emitter which is shown diagrammatically in the lower right-hand corner in Fig. 9 and in a sectional view in Fig. 4. The emitter consists of stationary contact points 81 and a rotating switch member 82. From Fig. 4, it will be noted that the rotatable switch member 82 is carried by the disc 51 and thereby rotates synchronously with the feeding of the card. Current is supplied to the switch member 82 by means of a current supply ring 84 against which presses a spring contact ball 83 carried by the disc 51, and said spring-pressed contact ball 83 is in electrical connection with the switch member 82. This construction is shown diagrammatically in Fig. 9 and in constructional detail in Fig. 2.

Combinational hole translator

The translator is, preferably, of a construction which is well known and which constitutes the second storing set of the storing mechanism as well as the devices for controlling the sorting mechanism. The constructional details are shown in Fig. 5 and the same construction is diagrammatically shown in Fig. 9.

Four electromagnets 90 are designated in Figs. 1 and 9 by the designations, I, II, III, IV, and the electromagnets 90 are coordinated with the respective four index point positions in each of the card columns so that upon the occurrence of perforations at such index point positions, the respective electromagnets 90 will be energized.

The electromagnets 90 are carried by a frame plate 60 (Fig. 5) and each is provided with an

armature 91 which, upon its attraction due to the energization of the related magnet 90, will unlatch a pawl 61 which is thereupon urged by a related spring 63 so as to cause a shoulder of the pawl 61 to pass beneath one arm of a bell crank 69. The bell cranks 69 are pivotally mounted on the frame plate 60 and the lower depending arms have pin and slot connections to a common operating bar 68 which is operated by means of a cam 67.

Pivotaly mounted to the pawls 61 are push rods 62 which are slidably mounted and normally held upwardly by means of coil springs surrounding the rods. The upward movement of each push rod 62 to the position shown in Figs. 5 and 9 is limited by means of any suitable stop device, such as a pin carried by the push rod 62. The lower end of the push rod 62 when depressed is adapted to rock a related arm 64 against the action of a compression spring 65 thereby permitting certain of the translator contacts 70 to open and causing certain other of said translator contacts 70 to close.

A common operating bar 72 which is reciprocated by means of a cam 71 carries pins 73 cooperating with the upper ends of latch arms 66 so that by the movement of the bar 72 to the right the latch arms 66 will be rocked thereby unlatching the previously rocked arms 64. In the event that a related magnet 90 has been energized the movement of the bar 68 to the left will rock the respective bell crank 69 and since the related pawl 61 has been unlatched it will depress the respective push rod 62 downwardly so as to engage the horizontal arm of the arm 64 thus positioning the contacts 70 from their normal positions.

A common operating bar 75 which is actuated by the cam 74 serves the purpose of restoring the pawls 61 to such position that they will again be normally latched by the armatures 91 of the electromagnets 90.

Manner of operation of the machine.

It will be recalled that a series of cards which are to be sorted are placed in the supply hopper and such cards are fed singly from the supply hopper to the analyzing brushes and when a selected column of each card is coordinated with the analyzing brushes a circuit will be closed as will now be described in connection with the wiring diagram shown in Fig. 9.

This circuit extends from one line side 100 to wire 101, current supply ring 53, spring-pressed contact member 54, contact point 52, current supply ring 51, contact member 57, wire 102, card lever contacts 29 (which are shown in Fig. 1 and are of a form well known in the art), wire 103, contact plate 17, through the analyzing brushes 16 which pass through the holes in the selected card column, through wires 104 connected to the brushes 16 which pass through such holes, to the respective magnets 90, and wire 105 to the other line side 110. By the above described circuit certain of the magnets 90 will be energized. Each electromagnet 90 which is energized will attract its related armature 91 thereby unlatching, as previously described, the related pawl 61 which, thereupon, is urged by its spring 63 to cause its shoulder to pass beneath the horizontal arm of the related bell crank 69.

In the showing of Fig. 5, it has been assumed that the previous card analyzed and which is to be sorted represented the numeral "6." Accord-

ing to the code shown in Fig. 8, holes in a selected card column will be at the first and fourth index point positions thereby causing the previous energization of the magnets 90 designated by the characters I and IV. In the previous cycle of operation of the machine this caused the rocking of the related arms 64 and the latching thereof by means of the latch arms 66 so that the translator contacts 70 related to such index point positions will have been adjusted as shown in Fig. 5, and by means of the latch arms 66 remain in such adjusted position so as to cause the sorting of this card.

The translator contacts 70 which are adjusted are held adjusted a sufficient length of time so as to permit sorting of all of the cards representing the digits 0 to 9, inclusive, and 10, 11, and 12, it being noted that for the sorting of cards representing "0" the card travels almost the complete distance occupied by the staggered ends 33 of the sorting blades before the sorting magnet 21 is energized. When the translator contacts 70 have been adjusted and remain in adjusted position until the sorting of the cards is completed the translator contacts are restored to normal by the unlatching of the arms 64. This is effected, as previously described, by means of the cam 71 which rocks the bar 72 causing the rocking of the latching arm 66 and the unlatching of the arms 64 which are thereupon urged by their spring 65 to occupy their normal positions. In this manner the translator contacts 70 are restored to normal position so they may be in such a condition for a previous and subsequent adjustment in accordance with the next card to be sorted.

It is also assumed that the next card which passes through the machine represents the number "12" which is represented by holes located at the first, second, and third index point positions, as will be clear from Fig. 8.

When such card is coordinated with the analyzing brushes the electromagnets designated I, II, and III will be energized thereby unlatching the related pawls 61 and causing the springs 63 to rock them to the position shown in Fig. 5. This completes the adjustment of the first storing set and there will then be effected the transfer of the adjustment of the first storing set to the second storing set.

When the last card column of the card has passed the analyzing brushes 16 the bar 68 will be moved to the left as viewed in Fig. 5 thereby rocking all of the bell cranks 69 in a clockwise direction. Thus those pawls 61 which have been unlatched will now be rocked downwardly thereby depressing the related push rods 62 to effect the rocking of the related arms 64 and secure the desired adjustment of the translator contacts 70. Due to the fact that the arms 64 are latched by the pawls 66 in their positions of adjustment, the adjustment of the translator contacts 70 will be retained irrespective of the fact that the coil springs surrounding rods 62 are effective to restore the push rods 62 upwardly which will be permitted when the common operating bar 68 is restored to its right-hand normal position under control of its operating cam 67. Thereafter the restoration of the pawls 61 is effected by means of the cam 74 which effects a reciprocation of the bar 75 so that the pawls 61 are all rocked to their normal positions so that they may again be latched by their respective armatures 91, placing the parts of the first storing set in normal

condition for the subsequent adjustment effected by the next card to pass through the machine.

The adjustment of the translator contacts 70 has been completed at a time in the cycle of operation of the machine when the leading edge of a card is close to the terminating end 33 of the sorting blade which leads to the "12" pocket. Since it is assumed in the previous explanation that the card to be sorted represented the number "12", at the time the translator contacts 70 have been adjusted and the card to be sorted is close to the "12" sorting blade, the switch member 82 will be in electrical contact with the "12" contact point 81 which is connected to the "12" line of the translator. A circuit will be completed which is described as follows: from the line side 100, wire 106, to the translator contacts 70 which have been closed so as to convert the combinational reading to a single reading, to the "12" line, the related contact point 81, the switch contact 82, the current supply ring 84, wire 107, the magnet of a relay 120, wire 108, sorting magnet 21, and wire 109 to the other line side 110. The sorting magnet 21 will thereupon be energized and a stick circuit therefore will be closed through the relay contacts 121, wire 112, cam operated contacts 111 to the line side 100. The contacts 111 are closed by means of a cam 76 at the desired time so as to close the holding circuit just described.

The energization of the sorting magnet 21 will cause the feeding of the card so that it will be directed by the appropriate sorting blade into the "12" pocket.

Assuming that the card to be sorted represents "5", it will be obvious that the translator contacts 70 are so adjusted so as to select the "5" line and by means of the contact of the switch member 82 with the "5" contact 81 of the emitter the sorting magnet 21 will be energized at the time the leading edge of the card is closely adjacent the sorting blade which leads to the "5" pocket.

The sorting magnet 21 and the magnet of the relay 120 are deenergized at the time the translator contacts 70 of the second storing set are restored to normal by the opening of contacts 111 which is effected under control of the cam 76. Thereupon the armature of the sorting magnet 21 will be positively restored to its normal position by means of a cam 28. This cam is secured to one of the feed roller shafts of one of the sets of feeding rollers 13, as is shown in Fig. 1.

While there has been shown and described and pointed out the fundamental novel features of the invention as applied to a single modification it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. In a cyclically operable sorting machine controlled by individual records, one to be passed through the machine in each cycle of machine operation, each of said records comprising a plurality of superposed decks of perforations arranged in columns which are transverse to said

decks, and wherein the deck arrangement and number of columns make the records longer in a direction parallel to said columns, the combination of analyzing means common to all of said decks and coordinated in succession with the columns of a selected deck, means for selectively associating a selected deck with said analyzing means, means for feeding said records past said analyzing means in a direction transverse of said columns, sorting mechanism controlled by said analyzing means for sorting the records according to a selected column, a member for controlling the effectiveness of said analyzing means, means for moving said member synchronously with the successive coordination of the record columns with said analyzing means for causing said analyzing means to be effective for analysis at the time a selected record column of a selected deck is coordinated with the analyzing means, and record column selecting means comprising an adjustable device having different settings, each setting corresponding to a selected record column, for causing by a setting thereof a joint cooperation with said member to render said analyzing means effective at the time the selected column is coordinated therewith, whereby the feeding of the record transverse to the direction of its columns and the joint cooperation of said selecting means and member enables the sorting of each record in a cycle of operation of the machine having a duration governed by the shorter dimension of the record.

2. In a cyclically operable sorting machine controlled by individual records, one to be passed through the machine in each cycle of machine operation, each of said records comprising a plurality of superposed decks of perforations arranged in columns which are transverse to said decks and wherein the deck arrangement and number of columns make the records longer in a direction parallel to said columns, the combination of analyzing means common to all of said decks and successively coordinated with the columns of a selected deck, means for selectively associating a selected deck with said analyzing means, means for feeding said records past said analyzing means in a direction transverse of said columns, sorting mechanism controlled by said analyzing means for sorting the records according to a selected column, a contact member for closing a circuit to said analyzing means, means for moving said contact member synchronously with the successive coordination of the record columns of a selected deck with said analyzing means to provide a circuit closing position for each record column, and record column selecting means comprising an adjustable device including a supplemental contact member having different settings determined by the adjustable device, each setting corresponding to a selected record column, for causing by a setting thereof a joint cooperation with said member to effect a circuit closure to said analyzing means at the time the selected column is coordinated with the analyzing means, whereby the feeding of the record transverse to the direction of its columns and the joint cooperation of said contact members enables the sorting of each record in a cycle of operation of the machine having a duration governed by the shorter dimension of the record.

MICHAEL MAUL.
